(57) **CLAIM**

The ornamental design for a miniature plant growing device with water vapor cycle, as shown and described.

DESCRIPTION

FIG. 1 is a top perspective view of a miniature plant growing device with water vapor cycle design showing my new design.

FIG. 2 is a front view of the miniature plant growing device with water vapor cycle.

FIG. 3 is a rear view of the miniature plant growing device with water vapor cycle.

FIG. 4 is a left view of the miniature plant growing device with water vapor cycle.

FIG. 5 is a right view of the miniature plant growing device with water vapor cycle.

FIG. 6 is a top view of the miniature plant growing device with water vapor cycle.

FIG. 7 is a bottom view of the miniature plant growing device with water vapor cycle.

FIG. 8 is a bottom perspective view of the miniature plant growing device with water vapor cycle; and,

FIG. 9 is a perspective view of the miniature plant growing device with water vapor cycle in the closed state.

The broken lines in the drawings depict environmental subject matter that forms no part of the claimed design.

1 Claim, 9 Drawing Sheets
